UNITED STATES PATENT OFFICE.

HENRY HORAN, OF EAST ORANGE, NEW JERSEY, ASSIGNOR TO HARTFORD CARPET COMPANY, OF HARTFORD, CONNECTICUT.

DESIGN FOR CARPET.

Specification forming part of Design No. **11,385**, dated August 26, 1879; application filed August 2, 1879.
[Term of patent 3½ years.]

To all whom it may concern:

Be it known that I, HENRY HORAN, of East Orange, in the county of Essex and State of New Jersey, have invented a new and original Design for a Carpet, of which the following is a specification.

The accompanying photograph illustrates my new design.

This invention relates to a new design for carpets, oil-cloths, and analogous fabrics; and consists in the novel grouping and configuration of figures hereinafter more fully pointed out.

The groundwork of the carpet is covered with clusters *a*, *b*, and *c* of flowers, all of which clusters appear to be united into one leafy mat by branches of maple-like leaves. The cluster *a* of flowers is flanked by lilies of the valley,

with star-flowers in the center. The group *b* contains a principal central star-flower, between smaller flowers and numerous maple-leaves. The group *c* is similar to, but less prominent than, the group *b*. Other flowers of smaller size are interspersed between the groups *a*, *b*, and *c*.

I claim—

The design for a carpet, consisting of the floral groups *a*, *b*, and *c* and intermediate leaves, substantially as shown.

The above specification of my invention signed by me this 30th day of July, 1879.

HENRY HORAN.
